[57] CLAIM

The ornamental design for industrial roll, as shown.

DESCRIPTION

FIG. 1 is a front elevational view of a new design for a industrial roll, the rear view being a mirror image thereof;

FIG. 2 is an edge elevational view as may be taken from the left side of FIG. 1;

FIG. 3 is an edge elevational view as may be taken from the right side of FIG. 1;

FIG. 4 is an edge view as may be taken from the top of FIG. 1, the bottom edge view being identical; and,

FIG. 5 is a perspective view of the industrial roll shown in an open position for mounting.
